UNITED STATES PATENT OFFICE.

LEE P. HYNES, OF CHICAGO, ILLINOIS, ASSIGNOR TO RAILWAY UTILITY COMPANY, OF CHICAGO, ILLINOIS, A CORPORATION OF ILLINOIS.

SLIDING-DOOR FASTENER.

1,223,389.

Specification of Letters Patent.

Patented Apr. 24, 1917.

Application filed July 1, 1912. Serial No. 706,885.

To all whom it may concern:

Be it known that I, LEE P. HYNES, a citizen of the United States, residing at Chicago, in the county of Cook and State of Illinois, have invented certain new and useful Improvements in Sliding-Door Fasteners, of which the following is a specification.

My invention is especially designed and adapted to meet the requirements of locks for the doors of freight cars, though, as will be seen from the following description thereof, it is well adapted to sliding doors for other purposes. With the ordinary hasp 10 and keeper now in common use for freight car doors, the latter are apt to be left unsecured and free to slide by inadvertence on the part of the railway employees or freight handlers, and the doors are also frequently 15 left open purposely for the sake of ventilation. When the car is moved with the door unsecured, it is driven backward and forward by the starting, stopping and jerking of the train and comes violently into contact 20 with the door jamb at one end of its movements and with the stop which limits its movements in the other direction, and is ultimately racked to pieces or injured to such an extent that the car is put out of 25 commission until repaired. When such a door is equipped with one of my locks, however, or preferably with two of them, one at either end of its path, it is automatically 30 caught and held the first time it is driven 35 into engagement with the lock and further shifting prevented. If but one lock is employed of course it is arranged upon the jamb or stop bar on the doorway to secure the door in closed position, but where it is 40 desirable to also secure the door in open position a lock is suitably located to engage with the rear edge of the door when the latter is open.

In order to meet the conditions imposed 45 by freight car construction, it is necessary that the catch of the lock yield readily under the impact of the door to permit the same to come to locking position and without undue strain upon the parts, and that it 50 shall not involve any small or delicate parts which are apt to be sheared by the impact of the door. It is further necessary, in view of the roughness of freight-car construction and the racking to which it is subjected, that 55 the parts interlock notwithstanding a con-

siderable vertical or lateral variation in the relative positions of the latch and keeper, and in order to escape injury as far as possible that they do not project unnecessarily beyond the face of the car side or into the doorway. My improved construction meets the above conditions and is further distinguished by the fact that the parts thereof may be cast in their ultimate form, thus doing away with any expensive machining or finishing.

In the accompanying drawing I have illustrated the preferred embodiment of my invention, and in the following specification I have described the same in detail, but it is to be understood that the disclosure of this specific form is for the purpose of exemplification only and that my invention is not limited thereto, but its scope is defined in the following claims.

In the drawings forming part of the application, Figure 1 represents a side view of a portion of a freight car, showing so much thereof including a doorway and door, as is necessary to an understanding of my invention; Fig. 2 is a front elevation of a portion of a jamb and door respectively having the members of my lock attached thereto; Fig. 3 is a vertical section upon the line 3—3 of Fig. 2; Fig. 4 a horizontal section upon the line 4—4 of Fig. 2 and Figs. 5, 6, 7 and 8 are isometric views of details which are described specifically below. The parts are designated by the same symbols of reference wherever they occur in the several views.

The freight car 9 and door 10 may be of any usual or approved construction, the latter being suspended by roller brackets 11, 11 upon a track 12 and retained against the car by guides 13, 13 as usual in such constructions. I have shown in the drawings a single lock A and keeper B attached to the door jamb and door respectively, but as stated above, if it be desired a similar lock and keeper may be mounted upon the stop 95 which limits the opening movement of the door and upon the other edge of the door respectively, if it be desired to lock the door in open position.

The keeper B consists of a face plate 14 105 formed with a pocket 15, the front wall 16 of which is substantially perpendicular to the face plate, the rear wall 17 and side walls 18, 19 being inclined as shown. The specific shape of this pocket is not essential how-

ever, but that shown is convenient for the reception of the catch of the lock and also for application to the door, it being only necessary in order to accommodate the keeper in position on the door to saw kerfs at the proper distance apart and substantially at the angle of inclination of the end walls of the cavity, and to remove the intermediate block by means of a chisel, the cut being made upon the angle of inclination of the rear wall of the cavity. The face plate is provided at its upper and lower edges respectively with cam projections 20, 21 for a purpose which will appear, and is secured to the door by bolts 22, 22.

The lock proper is composed of a pivoted latch member 23, a pivoted dog 24, a face plate 25 and a housing member 26, shown assembled in Figs. 2 and 3 and detached in Figs. 5, 6, 7 and 8. The latch member 23 is preferably cast integral and comprises a barrel 27 which constitutes the pivot thereof, a strap 28 projecting from the barrel intermediate its ends and substantially radial thereto, and a cammed catch 29 consisting of a triangular wing extending in a plane substantially at right angles to the strap 28 and offset from the axis of the barrel 27. A lug 30 projects from the face of the catch 29 at right angles thereto and is of such length as to be engaged by the upper cam projection 20 upon the keeper face plate when the latch is rotated or swung to a position in which said lug extends upwardly, as explained below.

The lock face plate 25 is formed near its upper end with a rectangular pillow block 31 the outer face of which is cylindrically concave, and at its lower end with a transverse corrugation 32 the inner face of which forms a bearing for the pintles of the dog 24 when the parts are assembled. A longitudinal slot 33 formed partly in the plane portion of the face plate and partially in the corrugation, receives and provides for the pivotal movement of the dog 24. The latter consists of an irregularly shaped plate 34 provided with trunnions 35, 35, a finger hole 36 and a transverse opening or slot 37, which last, when the strap 28 is in engagement with the dog, is in register with a pair of similar slots 39, 39 in the strap 28, which slots may be used for sealing the lock if desired by inserting an ordinary or suitable seal therethrough.

The housing member 26 comprises a plane attaching plate 40 and a semi-cylindrical cover or housing 41, having an end wall 42, and adapted to fit over the pillow block 31 and to constitute with the latter a substantially cylindrical bearing for the barrel 27 of the latch. The housing is cut away intermediate its ends as at 43 to provide for the projection therethrough and swinging movement of the strap 28 of the latch.

The lock may be attached to the stop bar 44 without any preliminary preparation of the latter, and is assembled by thrusting the dog 24 through the opening 33 in the lock face plate until the pintles 35 thereof enter the corrugation 32, and projecting the strap 28 of the latch through the opening 43 in the housing until the barrel 27 occupies the concave thereof, the housing member then being applied to the lock face plate over the pillow block 31 and the whole structure attached to the stop bar by bolts driven through the bolt holes 45, 45, 45 of the face plate and the bolt holes 46, 46 of the housing plate.

When the lock has been thus assembled and secured to the stop bar as above described and the keeper plate properly located upon the door to coöperate therewith, the latch 23 normally hangs substantially vertical whether the door is open or closed, the dog 24 projecting through the longitudinal slot 47 in the strap with its cammed lip 48 occupying a position over the lower edge of the slot in the keeper as shown in Fig. 3. The engaging surfaces are such, however, that outward pressure exerted upon the strap readily lifts the dog to permit the strap to swing upward. If the door is closed the catch 29 of course rests within the pocket of the keeper B and the lock may be either secured by a padlock, the bar of which is passed through the finger hole 36 in the dog, or by a seal passed through the transverse registering openings 39, 37 in the strap and dog respectively, or by both if desired. To unlock the door it is only necessary to remove the padlock and seal if such have been attached as described, and swing the strap upward thus withdrawing the catch from engagement with the keeper. In order to close the door it is only necessary to throw it to closed position when the lip of the outer wall of the keeper wipes upon and past the cammed edge of the catch, rotating the latch until the outer wall of the keeper in the keeper passes beyond the nose of the catch, when the latter swings into the pocket, the strap at the same time swinging into vertical position in engagement with the dog as before described. If by any chance the latch is swung upward so far that it is caught or lodged with the strap and lug extending upwardly from the barrel thereof, movement of the door brings the upper cam 20 into engagement with the lug and dislodges the latch which swings to normal position. The additional cam 21 on the keeper plate performs no function in the construction when mounted as described but is only provided so that the keeper may be used in a reverse position with a lock of reverse construction, as for example, when a lock is to be applied to the rear edge of the door for holding it open. The pillow block

31 and cover member 41 are extended beyond their attaching plates so that when in position they extend beyond the edge of the stop bar to bring the catch member into proper position for coöperation with the keeper, and the end wall 42 upon the housing member receives the shock and longitudinal pressure transmitted to the latch barrel permitting the latch to rotate easily under the pressure, when the door engages the same.

It will now be seen that I have provided a lock which is automatic in its action and therefore prevents the destructive movements of the car door to which it is attached, which is readily formed by casting the parts without any machining or other expensive manipulation and which does not depend for effective operation upon nice adjustment of the parts but will act notwithstanding considerable vertical or lateral variation in the relative positions of the parts. It possesses the further advantages that it holds the door from lateral swinging when in engagement therewith and projects but slightly from the side of the car or into the opening therein, thus avoiding to a large extent contact with passing objects.

I claim:

1. A lock for sliding doors comprising a latch member and a keeper, the former comprising a mounting adapted to be attached to the jamb of a door and an oscillatory member, the latter comprising a barrel journaled in the mounting on a horizontal axis parallel to the face of the jamb, a catch projecting laterally from said barrel and having a beveled front edge, the keeper being adapted to be secured to the door to one side of the said barrel and to engage the beveled edge of the catch to swing the same to one side and then to engage the rear edge of the catch to prevent opening the door.

2. A lock for sliding doors comprising a latch member and a keeper, the latch member comprising a mounting adapted to be attached to the jamb of a door and an oscillatory member, the latter comprising a barrel journaled in the mounting on a horizontal axis parallel to the face of the jamb, a catch projecting laterally from said barrel and having a beveled front edge, a heavy arm on said barrel normally pendant and maintaining said catch yieldingly in a substantially horizontal position, the keeper being adapted to be secured to the door to one side of the said barrel and to engage the beveled edge of the catch to swing the same to one side and then to engage the rear edge of the catch to prevent opening the door.

3. A lock for sliding doors comprising a latch member and a keeper, the latch member comprising a mounting adapted to be attached to the jamb of a door and an oscillatory member, the latter comprising a

barrel journaled in the mounting on a horizontal axis parallel to the face of the jamb, a catch projecting laterally from said barrel and below the horizontal plane thereof, and having a beveled front edge, means for yieldingly mounting the oscillatory member with the catch in horizontal position, the keeper being adapted to be secured to the door to one side of the said barrel and to engage the beveled edge of the catch to swing the same to one side and then to engage the rear edge of the catch to prevent opening the door.

4. A lock for sliding doors comprising a latch member and a keeper, the latch member comprising a mounting adapted to be attached to the jamb of a door and an oscillatory member, the latter comprising a barrel journaled in the mounting on a horizontal axis parallel to the face of the jamb, a catch projecting laterally from said barrel and having a beveled front edge, a heavy arm on said barrel normally pendant and maintaining said catch yieldingly in a substantially horizontal position, the keeper being adapted to be secured to the door to one side of the said barrel and to engage the beveled edge of the catch to swing the same to one side and then to engage the rear edge of the catch to prevent opening the door, and a cam on said keeper adapted to engage said oscillatory member when the latter is oscillated to throw said arm above the barrel against the jamb and to tilt said arm outward to permit it to fall to pendant position.

5. A lock for sliding doors comprising a housing and a swinging latch mounted therein and comprising a barrel journaled in the housing, a laterally projecting beveled catch mounted upon the barrel, a depending strap also mounted upon the barrel and a pivoted dog engaging the strap.

6. A lock for sliding doors comprising a housing and a swinging latch mounted therein and comprising a barrel journaled in the housing, a laterally projecting beveled catch mounted upon the barrel, a depending strap also mounted upon the barrel, and a pivoted dog engaging the strap, the strap and dog being provided with registering perforations for the insertion of a seal.

7. In a lock for sliding doors, a keeper adapted to be secured to a door, a face plate adapted to be secured to the jamb of a door and having a pillow block, a housing mounted upon the face plate over the pillow block and forming therewith a bearing, a latch pivoted in said bearing and comprising a pendant member and a laterally projecting cammed catch adapted to coöperate with the keeper.

8. In a lock for a sliding door, a keeper adapted to be attached to a door in combination with a lock proper, comprising a face plate and a concave pillow block extending

across the same, a detachable housing mounted upon and secured to the face plate and embracing said pillow block, said housing being cut out intermediate its ends, a barrel 5 horizontally journaled between said pillow block and housing and a heavy strap projecting through the cut-out portion of the housing and a cam catch normally held in substantially horizontal position in the path 10 of the keeper by said strap.

9. In a lock for sliding doors, a face plate 25 having a transverse corrugation 32 near its lower end and a vertical slot 33 extending in said corrugation, a dog 24 having pintles 15 35 journaled in said corrugation, said dog

extending through said slot, a pillow block 31 also formed upon said face plate, a housing member comprising the securing plate 40 and a housing 41 embracing said pillow block and forming therewith a bearing, a 20 swinging latch comprising a barrel 27 mounted in said bearing, a strap 28 projecting from said barrel and a beveled catch 29 carried by the barrel and normally held in substantially horizontal position by said 25 strap.

LEE P. HYNES.
